ILLUMINATED GAME DISPLAY BOARD OR THE LIKE

William G. Tregurtha, Monroeville, Pa. (371 Mathews Road, Youngstown, Ohio 44512), and Harold J. Greene, 750 Truesdale Road, Youngstown, Ohio 44511

Filed Mar. 2, 1967, Ser. No. 6,037

Term of patent 7 years

(Cl. D34—5)

The figure is a front plan view of the illuminated game display board or the like.

The board is of conventional thickness and the back is plain and unornamented.

We claim:

The ornamental design for an illuminated game display board or the like, as shown and described.
